United States Patent

Des. 242,235
Patented Nov. 9, 1976

242,235

GAUGE CASING

Robert Edward Redmann, Orange, Conn., assignor to
Dresser Industries, Inc., Dallas, Tex.

Filed July 28, 1975, Ser. No. 599,502

Term of patent 14 years

Int. Cl. D10—07

U.S. Cl. D10—102

FIG. 1

FIG. 3

FIG. 6

FIG. 2

FIG. 5

FIG. 4

FIG. 1 is a front elevational view of gauge casing showing my new design;

FIG. 2 is a rear elevational view thereof;

FIG. 3 is a side elevational view thereof;

FIG. 4 is a top plan view thereof;

FIG. 5 is a bottom plan view thereof; and

FIG. 6 is a partially sectioned side elevation thereof.

I claim:

The ornamental design for a gauge casing, as shown.
